UNITED STATES PATENT OFFICE

WILLIAM H. LEVELLS, OF INDIANAPOLIS, INDIANA

DESIGN FOR A SMOKING PIPE

Application filed August 28, 1931. Serial No. 40,949. Term of patent 7 years.

To all whom it may concern:

Be it known that I, WILLIAM H. LEVELLS, a citizen of the United States, residing at Indianapolis, in the county of Marion and State of Indiana, have invented a new, original, and ornamental Design for a Smoking Pipe, of which the following is a specification, reference being had to the accompanying drawings, forming part thereof.

I claim:

The ornamental design for a smoking pipe as shown.

WILLIAM H. LEVELLS.
